UNITED STATES PATENT OFFICE

ANTHONY DOMBROWSKI, OF BROOKLYN, NEW YORK

LOCK

Application filed February 16, 1927. Serial No. 168,539.

My invention relates to improvements in fastening devices, and more particularly has reference to a device of the class described especially adapted for use upon travelling bags, luggage, trunks, and similar articles.

Referring to the accompanying drawings, I have illustrated in Fig. 1 in perspective, parts being broken away, a suitable form of fastener embodying an application of my invention. Fig. 2 is a similar view illustrating a modified form. Fig. 3 is a cross-section on the line 3—3 of Fig. 2, and Fig. 4 is a similar view to Fig. 3, showing the same in unlocked or opened position.

5 5, 6, indicate the two portions of the device, the former usually secured to the front of the luggage, as in the case of a suitcase, and the part 6 to the cover thereof, so that when in closed position the two parts are held together by the pivoted portion 7, 8 being a cam-like structure for operating the part 7. This cam-like portion is shown in modified form 10 in Fig. 2, where it is indicated by the reference character 9, and the same applies to the 20 holding device 10, which is of slightly different form to the part 7, serving a similar function in Fig. 1.

In both forms of the device, the outer housing 11 is preferably provided with base 30 prongs 12', which pass through the plate or escutcheons 5, 6, and are bent over thereunder to secure the housing in position, as shown, the same applying to the smaller housing 12, secured to the escutcheon or base 6. Within 35 this housing 11 is slidably mounted a channel-like structure 13, preferably having a closed end 14, and opened end 15. A flat steel spring 16 is preferably secured thereto by a rivet or other suitable means as indicated at 40 17, the free end of said spring being bent or formed substantially as shown, thus providing a seating for the cross-bars 18 of the finger-piece 9, forming a cam-like member, so that when the free end 19 of said cam-like member is lifted, the rectangular cross-bar portion having an enlarged central area serving as a tongue, lifts the free end of the spring 16, striking the shoulder 20 thereof, and 45 forcing the channel-like carriage 13 rightwardly to the position shown in Fig. 4. The 50

other end of the channel-like member 13 is cut-away to receive the square frame-like portion 10, and the outer casing 11, at the sides, is cut-away to allow for the longitudinal movement of the same when the channel-like carriage 13 is moved by the finger-piece 19. This frame-like holder 10 has a tongue-like portion 21, which engages beneath the open end 22, of the housing 12, when the fastener is in closed position, so that when the finger-piece 19 is elevated, as shown in Fig. 4, the frame holder 10 is pushed rightwardly, looking at Fig. 4, clearing the tongue 23 of the open end of the housing 12, and allowing the same to be thrown clear thereof, as indicated in dotted outline, thus allowing the cover of the bag or trunk to be lifted. When the cover is returned, the frame holder 10 is pushed back into the position for engaging the housing 12, and the finger-piece 19 is returned to the position shown in Fig. 3, thereby again drawing the tongue into the housing, securely locking the cover in position, said housing 12 having the usual guide tongue 24, which engages the open end of the housing 11 in the 75 usual manner.

The finger-piece 19 is also perforated, as indicated at 25, and a hole 26 is also preferably formed in the base portion 5 in alignment therewith, and likewise preferably a 80 half round hole 27 in the periphery thereof, as shown, to facilitate passing a wire through the said opening for sealing the fastener in locked position.

A modification of this arrangement is 85 shown in Fig. 1, where the cam-like finger-piece is preferably provided with a lever-like end to be engaged between the fingers for operating the same, said lever having a hole therethrough for the passage of the lug 29, 90 extending up from the base 5, also having a hole 30 for the passage of the wire 31, the free ends of which may be secured in the seal 32.

Of course it will be understood that various modifications may be made in the construction and arrangement of parts without departing from the spirit of the invention as claimed.

I claim:—

1. A fastener of the class described, hav- 100

ing an outer housing on one part and a slide-
able member therein, a cam-like finger-piece
pivoted in said outer housing and adapted
to engage said slideable member, engaging
means carried by said slideable member, and
a housing on another part of said fastener for
engagement with said engaging means, and
a spring within said first-mentioned housing
for direct engagement with said cam-like fin-
ger-piece.

10 2. A fastener of the class described, having
an outer housing on one part and a slideable
member therein, a cam-like finger-piece
pivoted in said outer housing and adapted to
15 engage said slideable member, engaging means
carried by said slideable member, and a hous-
ing on another part of said fastener for en-
gagement with said engaging means, and an
offset spring within said first mentioned hous-
20 ing for direct engagement with said cam-like
finger-piece.

25 3. A fastener of the class described, having
an outer housing on one part and a slideable
member therein, a cam-like finger-piece
pivoted in said outer housing and adapted to
30 engage said slideable member, cam-like engag-
ing means carried by said slideable member,
and a housing on another part of said fastener
for engagement with said engaging means,
and holding means for retaining said fastener
closed.

In testimony whereof I hereunto affix my
signature.

ANTHONY DOMBROWSKI.
